Primary Examiner—Prabhakar Deshmukh*Assistant Examiner*—Derrick Holland(74) *Attorney, Agent, or Firm*—Kenyon & Kenyon LLP(57) **CLAIM**

The ornamental design for an electric motor device, as shown and described.

DESCRIPTION

FIG. 1 is a perspective view of an electric motor device showing my new design.

FIG. 2 is another perspective view thereof.

FIG. 3 is a front view thereof.

FIG. 4 is a left side view thereof, the right side view being a mirror image of the left side view.

FIG. 5 is a rear view thereof.

FIG. 6 is a top view thereof; and,

FIG. 7 is a bottom view thereof.

The “SEW” logo shown in broken lines represents unclaimed subject matter and forms no part of the claimed design.
